MULTIHIGH ROLLING MECHANISM

Application filed July 18, 1931, Serial No. 550,922, and in Germany July 29, 1930.

This invention relates to improvements in and relating to multi-high rolling mechanisms.

For the purpose of rolling strips, bands and sheets only twin roll mechanisms were used originally. Later on the operating rolls were made thinner and were mounted between supporting rolls so as to transfer the forces which were taken up by the rolling mechanism during the rolling operation to the thicker supporting rolls. This superposition of the rolls led to the construction of the known four and six high rolling mechanisms.

There are certain limitations of the six-high mills which become particularly important as I reduce the diameter of the operating rolls. The present invention aims to provide rolling mechanism by which such disadvantages are obviated.

The accompanying drawing illustrates an embodiment of the invention;

Fig. 1 is a diagrammatic end view;

Fig. 2 is a vertical sectional view showing the two operating rolls and their driving mechanism;

Figs. 3 and 4 are respectively sectional views of details.

Referring to the embodiment of the invention illustrated, a pair of operating rolls A, A' are backed or supported by primary supporting rolls B, B' for the operating rolls A and C, C' for the operating roll A'. The primary supporting rolls are in turn supported by secondary supporting rolls E, E' and E'' for the rolls B and B', and F, F' and F'' for the rolls C and C'.

This construction is particularly useful where the operating rolls have to be made very small. It is a condition of such apparatus that the plane D, which is tangent to the supporting rolls B and B' must pass through the corresponding operating roll A so that the latter may project beyond such plane in order to engage the work. The fact that there are two supporting rolls B and B' for the one operating roll puts a limit on the size of these two supporting rolls. They cannot be made large enough to touch each other above the operating roll; nor placed high

enough to make such contact with each other.

Furthermore, if we assume a constant diameter and fixed position of the supporting rolls, any reduction in diameter of the operating rolls moves the latter farther into the bight of the supporting rolls and brings the pressure of the latter more and more toward the horizontal direction which is least effective in resisting the vertical strains of use. Thus the supporting rolls (where two supporting rolls are used for each operating roll) are limited in maximum diameter, first, by the need to keep them well away from contact with the work passing through the operating rolls, and second, by the requirement that they bear on the operating roll in a direction having a substantial vertical component.

Ordinarily rolls like B and B' would be about twice or two and a half times the diameter of their operating roll A. If the operating rolls A and A' were made very small, for example, with a diameter of only thirty to fifty millimeters, the supporting rolls would have to be of correspondingly small diameters; and for mechanism requiring very high pressures would not be capable of withstanding the strains of the rolling operation.

In order to make a rolling mill with a very small operating roll, and at the same time to secure a high pressure, I propose to use rolls B, B' and C, C' as primary supporting rolls, to make these comparatively small so as to avoid the disadvantages referred to above, and to provide a supplementary set of supporting rolls E, E', E'' and F, F', F'' supporting the reaction of the primary rolls. Various arrangements and sizes of this supplementary set of supporting rolls may be provided. I propose to make them as illustrated, about twice or two and a half times the diameter of the primary supporting rolls, with E and E'' bearing on the outsides of the separate rolls B and B' and with the central roll E' bearing against both the rolls B and B' and located in line above the operating roll A; and similarly for the lower supporting rolls.

The operating rolls of such a rolling mechanism are preferably not provided with piv-

ots and are in the form of solid cylinders or as hollow cylinders of which the inner surface has not been carefully machined. When hollow cylinders are used, it is only necessary to simply fit these on the driving shafts and to connect them thereto by a suitable coupling device. When it is desired to roll with an extremely small diameter it is no longer possible to use hollow rolls. The drive of the operating rolls is then preferably effected in the manner illustrated in Figure 2. In Figure 3 A, A' again indicate the operating rolls. At one end these are connected by a coupling device G, G' to the shafts J and J' respectively. The drive is effected by means of toothed wheel gearing from a common shaft K, in which case one of the operating rolls is driven through intermediate gear L so that this roll is rotated in the opposite direction to the other. The coupling devices are preferably provided at different ends of the two operating rolls. The rolls may then be formed of simple smooth cylinders and the engagement may be effected by a bolt or pin passed through a transverse hole.

Particularly in connection with the intermediate rolls B, B' and C, C' it is advisable in some circumstances not to provide these in the usual manner with shafts rigidly connected to the roll body. It is generally preferable to fit the rolling cylinders in the manner of a roller bearing on a rigid non-rotating shaft. A diagrammatic illustration of such rollers is illustrated in Figure 3, in which M indicates the fixed shaft, B the roller and O the bearings of this roller on the shaft. In other cases it may be preferable to form the supporting rolls or both the supporting rolls and the intermediate rolls in this manner. Finally, the intermediate rolls may consist of simple cylinders without pivots. The intermediate rolls are preferably pressed by a spring mounting N against the outer supporting rolls.

In many cases, namely when rolling hot material, it is advisable to cool the various rollers. In the case of the operating rolls, this cooling is preferably effected from the free end, which is not connected to the driving shaft, by fitting cooling pipes for example into a bore of the rolls, a cooling medium being passed through these pipes. In the case of the intermediate rolls similar pipes may be fitted into the shaft, which is preferably stationary. The pipes may extend along the whole length of the shaft and are introduced from one end, or when rolls with pivots are used short sections of pipes may be fitted from both ends into the pivots, as shown in Fig. 4 wherein the cooling pipes are indicated by P. If a rolling mechanism according to the present invention is to be used for hot rolling, the pivots of the intermediate rolls and supporting rolls are preferably cooled.

When using a rolling mechanism according to the present invention it is possible in an economical manner to use operating rolls of materials which have proved uneconomical in the previously usual rolling mechanism requiring large operating rolls. For example operating rolls in a rolling mechanism according to the present invention may be constructed metal of the so-called "hartmetall" (hard metal) type which generally comprise alloys containing hard constituents such as tungsten carbide, tantalum carbide, molybdenum carbide and also may contain such metals as tungsten, molybdenum, tantalum with possible additions of iron, nickel or cobalt.

The costs of such small rolls are naturally low and in addition there is less waste when hardening the rolls. As further by the small rolls a higher specific pressure and thus a greater rolling effect is accomplished, the cost of operation of the rolling mechanism is also cheaper than that of the previously known rolling mechanisms.

As the drawing-in action of smaller rollers for the material is only slight, it is necessary in many cases, when using very small operating rolls, to point or reduce in size the head of the material to be rolled before introducing it into the operating rolls.

Any usual or suitable method and apparatus may be used for this purpose.

The location of the supporting rolls is advantageous in securing the proper direction and balance of pressures and in attaining compactness of the complete stand of rolls.

The rolls B and B' bear on the roll A at points beyond its center so that the pressure has a substantial vertical component. The rolls E and E' bear on the rolls B and B' at about the same angle. That is to say, the centers of A, B and E are approximately in a straight line and also the centers of A, B' and E''. The reaction from the outer roll, therefore, is transmitted practically straight through the intermediate roll to the operating roll. The central roll E' extends very little above the two side rolls E and E''. It engages both the rolls B and B' so as to maintain their spacing and location, the roll E' being in vertical alignment with the operating roll A.

Thus in a very compact space the reactions of the backing-up rolls are transmitted most efficiently to the operating rolls. The same conditions exist for the lower operating roll A' and its supporting rolls C, C' and F, F' and F''.

The principle here described may be continued further and incorporated in twelve high rolling mechanisms to twenty high rolling mechanisms and so on.

The principle is not limited to the drive of the operating rolls. As all the rolls have the same peripheral speed, the operating rolls be-

ing the smallest have the highest number of revolutions. If the operating rolls are driven there is the lowest ratio of transmission between the motor and the rolls. In many cases the motor may be connected directly to one of the rolls, or each of the operating rolls may be connected directly to a motor in the known manner. According to the particular conditions the drive may be also connected to the intermediate rolls or to the supporting rolls.

I claim:-

1. A rolling mechanism comprising a pair of operating rolls adapted to engage the opposite faces of the work, a plurality of primary supporting rolls bearing against each of said operating rolls and located at opposite sides thereof, beyond the plane of the work and tangent to the operating roll at points beyond the center lines of the latter, and a plurality of secondary supporting rolls bearing against the primary supporting rolls.

2. A rolling mechanism comprising a pair of operating rolls adapted to engage the opposite faces of the work, a plurality of primary supporting rolls bearing against each of said operating rolls and located at opposite sides thereof, beyond the plane of the work and tangent to the operating roll at points beyond the center lines of the latter, and a plurality of secondary supporting rolls bearing against the primary supporting rolls, the ratio of the diameters of the primary supporting rolls to those of the operating rolls not exceeding 5 to 2.

3. A rolling mechanism comprising a pair of operating rolls adapted to engage the opposite faces of the work, a plurality of primary supporting rolls bearing against each of said operating rolls and located at opposite sides thereof, beyond the plane of the work and tangent to the operating roll at points beyond the center lines of the latter, and a plurality of secondary supporting rolls bearing against the primary supporting rolls, the ratio of the diameters of the primary supporting rolls to those of the operating rolls as well as the ratio of the diameters of the secondary supporting rolls to those of the primary supporting rolls not exceeding 5 to 2.

4. The rolling mechanism of claim 1, the operating rolls being coupled directly to a drive shaft and being held in position by the primary supporting rolls bearing thereagainst.

5. The rolling mechanism of claim 1 and means for driving the operating rolls consisting of shafts at opposite sides of the mechanism each one coupled to an end of one of the operating rolls.

6. The rolling mechanism of claim 1, the supporting rolls being hollow in combination with stationary shafts passing through

said rolls and antifriction bearings between said shafts and their respective rolls.

7. The rolling mechanism of claim 1, the operating rolls being small rolls comprised of metal of the so-called hartmetall type. 70

8. The rolling mechanism of claim 1, the operating rolls being very small of the order of 30 to 50 millimeters diameter, the ratio of the diameters of the primary supporting rolls to those of the operating rolls not exceeding 5 to 2. 75

9. The rolling mechanism of claim 1, the operating rolls being very small of the order of 30 to 50 millimeters diameter, the ratio of the diameters of the primary supporting rolls to those of the operating rolls not exceeding 5 to 2. 80

10. The rolling mechanism of claim 1, the secondary rolls being three in number with a central one bearing on both the primary supporting rolls and an outer one bearing on each of the supporting rolls. 85

11. The rolling mechanism of claim 1, the operating rolls being very small of the order of 30 to 50 millimeters, the ratio of the diameters of the primary supporting rolls to those of the operating rolls and also the ratio of the diameters of the secondary supporting rolls to those of the primary supporting rolls not exceeding 5 to 2, the secondary supporting rolls being three in number, a central one located in vertical alignment with the operating roll and bearing on both the primary supporting rolls and two outside rolls bearing on the primary supporting rolls in such locations as to bring their centers in substantial alignment with the center of the contacting primary supporting roll and the operating roll. 95

In testimony whereof I affix my signature.
